US0D1071237S

(12) **United States Design Patent** (10) **Patent No.:** **US D1,071,237 S**
(45) **Date of Patent:** **** Apr. 15, 2025**

(54) **MYOFASCIAL RELEASE TOOL**

(71) Applicant: **Jonathan Axel Carlson**, Bowie, TX
(US)

(72) Inventor: **Jonathan Axel Carlson**, Bowie, TX
(US)

(**) Term: **15 Years**

(21) Appl. No.: **29/947,244**

(22) Filed: **Jun. 13, 2024**

Related U.S. Application Data

(63) Continuation-in-part of application No. 18/592,134, filed on Feb. 29, 2024, and a continuation-in-part of application No. 29/925,614, filed on Jan. 25, 2024, now Pat. No. Des. 1,035,025.

(57) **CLAIM**

The ornamental design for the myofascial release tool as shown and described.

DESCRIPTION

FIG. 1 is a front perspective view of the myofascial release tool showing my new design;

FIG. 2 is a left side view thereof;

FIG. 3 is a right side view thereof;

FIG. 4 is a top view thereof;

FIG. 5 is a bottom perspective view thereof;

FIG. 6 is a bottom view thereof;

FIG. 7 is a front view thereof; and,

FIG. 8 is a rear view thereof.

The broken lines shown in the Figures depict portions of the article that form no part of the claimed design.

1 Claim, 6 Drawing Sheets
